UNITED STATES PATENT OFFICE.

WILLIAM IRELAND DAVIES, OF BUCKNELL, ENGLAND.

BOX FOR CONTAINING BELTS OF CARTRIDGES FOR USE IN MACHINE-GUNS.

1,213,755.

Specification of Letters Patent. Patented Jan. 23, 1917.

Application filed September 11, 1915. Serial No. 50,142.

To all whom it may concern:

Be it known that I, WILLIAM IRELAND DAVIES, a subject of the Kingdom of Great Britain, residing at Bucknell, in the county of Salop, England, have invented certain new and useful Improvements in Boxes for Containing Belts of Cartridges for Use in Machine-Guns, of which the following is a specification.

10 This invention relates to those boxes which are used for containing belts of cartridges for use in machine guns, and which are of two kinds, viz. those which contain a single belt of cartridges, and which are attached 15 in position upon the machine gun for feeding the belt of cartridges into the gun, and those which are arranged to contain several belts of cartridges, and which are used for refilling the aforementioned boxes containing 20 a single belt of cartridges. Such boxes require to be made of a width which will allow of the belt containing the cartridges being freely allowed to leave the box as the belt is being withdrawn either for feeding 25 into the machine, or for transference from the supply box, consequently, for this reason there is a substantial amount of play allowed between the ends of the cartridges and the sides of the boxes, and as the boxes in the 30 course of transport are liable to a considerable amount of shaking and rough usage, it has been found that the cartridges become shaken from their fixed position in the belt, with the result that as they are fed into the 35 machine a jamming action at times takes place at the breech of the gun owing to such displacement of the cartridges in the belt.

The object of this invention is to avoid 40 the possibility of such displacement of the cartridges taking place, while in the box, and at the same time to allow perfect freedom for the exit of the belt of cartridges from the boxes as they are fed into the machine or withdrawn from the supply boxes, 45 the improvements consisting of padding the inside of that side of the box against which the noses of the cartridges butt and hinging the lower part of this side of the box, so that the upper part may be opened to a 50 limited extent, thus enabling the belt of cartridges to be freely inserted or withdrawn, provision also being made for locking the side in the closed position by which the padded faces are arranged to press against 55 the noses of the cartridges and retain them

tightly in position in the box when such boxes are in the course of transport, the locking and unlocking of the side being effected through the medium of the top lid, in such a manner that when the lid is opened 60 the side automatically opens out and leaves the belt of cartridges free for withdrawal.

In order that this invention may be clearly understood and easily carried into practice, reference may be had to the appended two 65 sheets of drawings, upon which:—

Figure 1 is a view of a box containing cartridge belts, and from which the machine gun is directly fed. Fig. 2 is a similar view to that of Fig. 1, but showing the box 70 open. Fig. 3 is a cross section through Fig. 1 showing the cartridges and belts in dotted lines. Fig. 4 is a view of a box used for the supply of two or more belts of cartridges. Fig. 5 is a view of the box shown 75 in Fig. 4, but when open showing the one or sliding part of the lid just on the point of removal after the side has been opened. Fig. 6 is a view of a device for closing and locking the side of the box by the action of 80 shutting the lid. Fig. 7 is a cross section through part of the box when open showing a modification in the device for closing and locking the side of the box by the action of 85 shutting the lid.

In an embodiment of this invention, and referring to the boxes for the direct feeding of the machine gun, the exterior of the box A and the lid B are of identical formation to the boxes at present in use, the lid B being hinged at one end b^1 of the box and provided with a catch b^2 by which it is locked to the top at the reverse end of the box in the usual way. By these improvements the one side C of the box is hinged to the bottom at c^1 , so as to have a limited amount of outward movement at the top c^2 and the interior of this side of the box which is preferably the one facing the nose ends e^1 of the cartridges E is covered with a resilient pad 100 F, preferably of india rubber, and which is of a thickness slightly greater than the usual amount of clearance allowed between the ends of the cartridges and the sides of the box. The extent to which the top of the 105 side is allowed to be opened is limited by means of corner straps such as H, which are arranged to have a limited sliding movement on both ends of the box, such straps being sunk into the surface of the box, so 110

as to present a face flush with the ends and sides of the box.

The opening side C of the box when closed is locked in position by means of projecting studs K which are fixed to the underside of the lid of the box, such studs entering into suitable recesses M formed in the top edges of both the fixed and movable sides of the box, in such a manner that when 10 the side is pressed into the closed position and the lid is shut both the fixed and opening sides are firmly clamped together.

In the case of the supply boxes which are now used and which are double the length 15 of the aforementioned boxes for the machine, the lid is divided into two parts B and B³, one half being hinged at b¹ to the end, and the other half B³ having a sliding action, this part B³ being retained in position by the closing of the hinged part B, and to which the hinged part is also locked when closed by a catch b⁴, and in this case 20 also my improvement consists in padding the one side C and hinging the lower part 25 of that side of the box as before described, or by hinges formed of levers c² which are pivoted to the open lid at c³ and to the box projections a², the levers being pivotally connected at c⁴, the whole being so arranged 30 that the lower part of the opening side C is opened out, but to a less extent than the opening out of the upper part. The one end and center of the opening side is locked in the closed position by similar studs K on the 35 hinged lid and recesses M as also previously described, while at the reverse end of the box the moving side C of the box is locked in the closed position by means of a projecting stud N or studs upon the end of, and 40 in the same plane as the sliding lid B³, which stud N enters into a hole c⁵ in a projecting plate fixed to the top of the end of the opening side, and which also enters into a recess a¹ in the fixed end of the box, the 45 nose of such projection being of a wedge shape for the purpose of drawing the opening side of the box tightly into the closed position.

The noses of the studs K may be wedge or 50 cam shaped as illustrated in Figs. 6 or 7, and the straps H so arranged as to prevent the side C opening beyond the wedge or cam projection, so that when the lid is forced down the wedge or cam shaped projections 55 enter the recesses M and bring the open side into its completely closed position, at the

same time locking it there by the securing down of the lid by the catch b².

A rubber or other strip J may be secured 60 along the bottom of the box near the open side, so as to raise the noses of the cartridges in the bottom fold of the belt into a position that they are free of the padded face to the cover when the side is opened.

If desired suitable springs may be inserted 65 between the box and the opening sides, so as to insure the side automatically opening out immediately upon the opening of the lid.

What I claim as my invention and desire 70 to secure by Letters Patent is:—

1. A cartridge box comprising four side walls a base and a top, one of said sides being hingedly secured, along its lower edge, to the base member, the hinged lid of said 75 box being hingedly secured to the upper edge of one of the sides of the box, and being provided with means adapted to overlie the upper edge of the side of the box.

2. A cartridge box comprising four walls, 80 a base and a lid, one of said walls being hingedly secured along its lower edge to the base, a lid being hingedly secured to one of the upper edges of another wall, and means secured to the lid and the side wall which is 85 capable of being swung outwardly so that when the lid is lowered the said side wall is automatically swung into a closed position.

3. A cartridge box comprising four walls, 90 a base and a lid, one of said walls being hingedly secured along its lower edge to the base, a lid being hingedly secured to the upper edge of another wall, and means comprising two wedge members adapted to co-operate with one another, one of said wedge 95 members being secured to the lid, the other to the side wall so that when the lid is lowered the side wall automatically swings into a closed position.

4. A cartridge box comprising four walls, 100 a base and a lid, one of said walls being hingedly secured along its lower edge to the base, said lid being hingedly secured to the upper edge of one of the sides, and means comprising a resilient pad secured to the 105 inner face of the hinged side wall.

In witness whereof I have hereunto set my hand in the presence of two witnesses.

WILLIAM IRELAND DAVIES.
